UNITED STATES PATENT OFFICE.

AXEL JOHNSON, OF EVERETT, WASHINGTON.

BOARD-LOWERING DEVICE.

1,177,705.

Specification of Letters Patent.

Patented Apr. 4, 1916.

Application filed August 7, 1915. Serial No. 44,342.

To all whom it may concern:

Be it known that I, AXEL JOHNSON, a citizen of the United States, residing at Everett, in the county of Snohomish and State of Washington, have invented certain new and useful Improvements in Board-Lowering Devices; and I do hereby declare the following to be a full, clear, and exact description of the invention, such as will enable others skilled in the art to which it appertains to make and use the same.

My invention relates to new and useful improvements in board lowering devices and more particularly to that class adapted to be used in connection with saw mills for lowering the board into engagement with the offbearing table or rollers, and my object is to provide, in connection with the offbearing rollers, pivotally mounted standards adapted to engage the board or cant as it is sawed from the log and lower the same upon the rollers.

A further object is to provide means at the lower ends of the standards to hold the board in engagement therewith.

A further object is to so mount the standards that they will swing in the arc of a circle and move to a position below the upper surface of the offbearing rollers and out of engagement with the board. And a further object is to provide means for raising and lowering the standards.

Other objects and advantages will be hereinafter set forth and more particularly pointed out in the accompanying specification.

In the accompanying drawings which are made a part of this application, Figure 1 is a transverse vertical sectional view showing the board lowering device in operative position. Fig. 2 is a vertical longitudinal sectional view through the supporting frame and device, and Fig. 3 is a top plan view thereof.

Referring to the drawings in which similar reference numerals designate corresponding parts throughout the several views, 1 indicates the frame work which may be constructed in any preferred manner such as is in common use in saw mills, said frame work providing a support for the saw carriage 2 used for moving a log 3 toward the usual form of saw (not shown).

Positioned adjacent one edge of the saw carriage is a frame 4 in which is mounted a plurality of offbearing rollers 5, one end of the rollers having beveled gears 6 with

which mesh similar gears 7 carried by a driving shaft 8, and when said shaft is rotated, the various rollers are likewise rotated to remove the board or cant 9 after the same has been sawed from the log, any suitable means being employed for driving the shaft 8.

In order to prevent the board from dropping with force upon the rollers, I provide a plurality of standards 10 which are pivotally mounted at a point adjacent their longitudinal centers between the straps 11, the lower ends of said straps being pivotally mounted between ears 12 carried by bolsters 13, said bolsters extending transversely of the frame 4 and between the rollers. The lower end of each standard is provided with a lateral extension 14 in which is formed a slot 15 to receive the pivot pin 16 employed for pivotally attaching the straps 11 to the ears 12, said slot extending longitudinally of the extension 14 and limits the swinging movement of the standard. When the standard is first elevated, it is thrown to a substantially vertical position, as shown by dotted lines at 17 in Fig. 1, but when the board is sawed from the log and the lower edge thereof strikes the frame 4, the board, in its outward movement, contacts the upper end of the standard and swings the standard in the arc of a circle to the position shown in full lines in Fig. 1, this action throwing the lower end of the standard outwardly and engaging a prong 18 at the lower end of the standard with the lower edge of the board and as the prong projects below the edge of the standard, the board will be held in position against the face of the standard and as the standard swings on its pivot, the board is carried away from the edge of the frame 4 and out of the path of the log carriage.

The standard 10 normally rests in a horizontal position as shown by dotted lines at 19 in Fig. 1, the end of the standard resting upon the end of the bolster on which it is pivoted, and in order to raise the standard to a substantially vertical position, a cylinder 20 is suitably positioned upon the frame work 1, said cylinder being operated by steam or compressed air which operates upon the piston 21 to move the same to the upper end of the cylinder, a piston rod 22 being pivotally attached to a crank arm 23 carried by a shaft 24, said arm being fixed to the shaft in any suitable manner so as to cause said shaft to rotate when the crank

arm is moved in the arc of a circle. Also fixed to the shaft 24 is a crank arm 25 to the outer end of which is pivotally attached a link 26, the upper end of the link being 5 in turn pivotally attached to the pivot pin 27 employed for pivotally attaching the standards to the straps 11.

When steam or air is admitted into the cylinder the piston 21 is moved to the upper 10 end of the cylinder, thereby rotating the shaft 24 and elevating the standards to the position shown by dotted lines at 17 in Fig. 1, the admission of the steam or air being controlled by a lever 28 from the 15 frame work 1. The lower end of said lever is connected with a valve 29 in such manner that when the lever 28 is swung back and forth, the valve will be opened and closed, and so long as the valve 29 is open, the 20 piston 21 will be held at the upper end of the cylinder and the standards held in an elevated position.

As soon as the board is properly seated upon the standards, the valve 29 is closed, 25 thereby releasing the pressure from below the piston so that the weight of the board upon the standards will swing said standards to a lowered position, the escape of the steam or air from the cylinder being so 30 regulated that the standards will be caused to gradually descend, thereby depositing the board upon the rollers without delivering a blow to the rollers.

After the board has been deposited upon 35 the rollers, the rotation of the rollers will carry the board to one end of the frame 4 where it is received by an attendant and properly disposed of for drying purposes, but should any obstructions, such as chips, 40 or the like, prevent the board from traveling over the rollers, the board can be again raised by elevating the standards in the manner previously described until such time as the obstruction is removed when the 45 board can be again lowered into engagement with the rollers.

In operation, while a board is being sawed, the lever 28 is operated to open the valve 29 so that steam or compressed air 50 will be admitted to the cylinder 20 through the pipe 30, said pipe extending from a suitable boiler or compression tank (not shown). Upon the admission of steam or air into the cylinder, the piston 21 will be elevated to 55 the upper end of the cylinder, thereby raising the standards 10 into position to receive a board cut from the log, said arms being held in their elevated position so long as the valve 29 is open. As soon as the 60 board has been properly engaged upon the standard, the lever 28 is returned to its initial position, thereby closing the valve 29 and releasing the pressure below the piston,

but in view of the restricted exhaust port 31 of the cylinder, it will require some time 65 for all of the steam or air to leave the piston, thus permitting the standards to gradually assume their lowered position and deposit the board gently upon the rollers.

This device can be readily attached to the 70 frame of the offbearing rollers at a minimum expense and by providing the same, the board can be more readily handled and will not injure the rollers when being deposited thereon. And it will likewise be 75 seen that the piston can be instantly operated at any time to raise the standards into position to receive the board or elevate the same after it has been deposited on the rollers.

Having thus fully described my invention what I claim as new and desire to secure by Letters Patent of the United States, is:—

1. A board lowering device for offbearing tables, comprising straps pivoted at their 85 lower ends to the table, standards pivoted substantially at their longitudinal centers to said straps and adapted to swing independently thereof, means to limit the swinging movement of said standards forwardly or 90 rearwardly, and means to raise and lower said straps and the standards pivoted thereto.

2. A board lowering device for offbearing tables comprising standards, pivotally 95 mounted straps pivoted to said standards, an engaging prong at the lower end of each standard, a slotted lateral extension at the lower end of each standard, a pin extending through said slot and limiting the swinging 100 movement of the standards with respect to said straps, and means to raise or lower the straps and standards attached thereto.

3. A board lowering device for offbearing tables comprising the combination with a 105 plurality of rollers and a supporting table therefor, of straps arranged in pairs and pivoted to said table and between the rollers, a standard pivoted between each pair of straps, said standards having swinging 110 movement independent of said straps, a lateral extension at the lower end of each standard having an elongated slot therein engaging the pivot pin at the lower end of the strap to limit the swinging movement of 115 the standard independently of the strap, a prong at the lower end of each standard, and means to raise and lower said straps and the standards carried thereby.

In testimony whereof I have signed my 120 name to this specification in the presence of two subscribing witnesses.

AXEL JOHNSON.
